UNITED STATES PATENT OFFICE.

WALTER J. DREW, OF GRAND RAPIDS, MICHIGAN, ASSIGNOR TO MICHIGAN CARPET SWEeper COMPANY, OF SAME PLACE.

CARPET-SWEeper.

SPECIFICATION forming part of Letters Patent No. 232,698, dated September 28, 1880.

Application filed July 7, 1880. (No model.)

To all whom it may concern:

Be it known that I, WALTER J. DREW, of Grand Rapids, in the county of Kent and State of Michigan, have invented certain new and useful Improvements in Carpet-Sweepers; and I do hereby declare that the following is a full, clear, and exact description thereof, reference being had to the accompanying drawings, and to the letters of reference marked thereon, which form part of this specification, in which—

Figure 1 is a bottom view, partly in section; Fig. 2, a central longitudinal section, and Fig. 3 a cross-section.

The nature of my invention consists in the employment, in a carpet-sweeper, of a torsion-spring, upon the ends of which the friction driving-wheels are journaled, and also in certain minor details, more fully described hereinafter, and specifically pointed out in the claims.

In order to enable others skilled in the art to which my invention appertains to make and use the same, I will now proceed to describe its construction and operation.

A represents the box or case of the sweeper, which is made in the ordinary form, and its ends B are provided with vertical slots b, as seen in Fig. 2.

a a are metal plates placed over the slots b, and provided in the center with an opening for the reception of the end of the operating-bail C. The plates a are at each end provided with a vertical slot, c, through which a screw is passed into the ends of the case, and the plates may be thereby adjusted up and down for the purpose of raising or lowering the brush, as will be seen by reference to the drawings.

C is the operating-bail, whose ends are bent toward each other and pass through the plates a a and slots b b into the brush-roller D, forming journals upon which the brush revolves, and may be sprung out at any time to release and remove the brush. The brush-roller D is at one end provided with the usual friction-pulley d to engage with the friction-wheels E E.

The wheels E E are journaled upon the ends of a spring, G, which, as seen in Fig. 1, is in U form, and may extend straight across the box or case, or it may be bent upward and lie along the top of the case, as shown in the drawings, and it is prevented from slipping backward, when in use, by the strap or staple o, as shown.

The ends of the spring upon which the wheels revolve abut against the end of the box or case, and the wheels, being confined between the end of the box and the dust-partition H, 55 cannot slip off the ends of the spring or get out of their position with reference to the brush-roller.

The wheels E are separated from the dust-chamber, as usual, by a partition, H, and this 60 partition is provided with horizontal slots h h, through which the spring G is passed, and allows a free movement to the ends of the same, which have a tendency to spring together and keep the wheels E pressed tightly against the 65 friction-pulley d, allowing for any inequalities in the wheels or pulley and insuring the operation of the brush when the machine is in use.

The box is provided with stationary dust-boards I I and dust-receptacle having sliding 70 bottoms J J. These bottoms are connected by wires or bars i i, and slide in grooves in the end B and partition H, or may be held in place by metal plates, which serve as ways on which they move. One of the bottoms is provided 75 with a handle or ring, f, by which the pans are slid sidewise a sufficient distance to empty the dirt from them.

The sweeper is operated in the usual way, and combines convenience and simplicity with 80 great economy of construction, has no parts liable to break or get out of order, and is readily taken apart for cleaning.

Having thus fully described my invention, what I claim as new, and desire to secure by 85 Letters Patent, is—

1. The combination of tension-spring G, having friction-rollers journaled upon its ends, with a revolving brush, substantially as and for the purpose described.

2. The combination, in a carpet-sweeper having a dust-receptacle on each side of the brush, of the connected and sliding bottoms J J with the dust-boards I I, substantially as and for the purpose set forth.

In testimony that I claim the foregoing as my own I affix my signature in presence of two witnesses.

WALTER J. DREW.

Witnesses:

HENRY J. FELKER,
WM. M. ROBINSON.
